HOT TOP

Benjamin F. Anthony, Cleveland Heights, Ohio,
assignor to The Ferro Engineering Company,
Cleveland, Ohio, a corporation of Ohio

Application July 30, 1942, Serial No. 452,845

7 Claims. (Cl. 22—147)

This invention relates to improvements in hot tops, and has reference particularly to means for producing projections on opposite surfaces of a sinkhead to minimize the slipping of crane bits in the handling of the ingots. Sinkheads are ordinarily tapered upwardly in order that the hot tops may be stripped therefrom. Such tapered surfaces do not offer a good grip for the crane bits. In accordance with my invention, projections are provided having either vertical surfaces for engagement with the crane bits or outwardly extending beads, the under surfaces of which may be engaged by the crane bits.

One of the objects of the invention is the provision of exceedingly simple means for accomplishing the stated purpose.

Another object is the provision of means of the character described which will permit stripping of the hot top from the ingot without damage to the hot top refractory elements.

A further object is the provision of a novel method of producing transverse beads or the like on ingot sinkheads.

Other objects and features of novelty will appear as I proceed with the description of that embodiment of the invention which, for the purposes of the present application, I have illustrated in the accompanying drawing, in which

Fig. 1 is a vertical sectional view of a hot top for ingot molds embodying the present invention;

Fig. 2 is a perspective view of a refractory lining block in which is formed a wedge-shaped recess or cavity employed in connection with the invention;

Fig. 3 is a perspective view of the upper portion of an ingot including a sinkhead having projections formed thereon in accordance with the invention; and

Figs. 4, 5, and 6 are vertical sectional views of modified forms of the invention.

In the drawing, the upper end of an ingot mold is indicated at 10 in Fig. 1, and in position in the mold there is shown a hot top of the composite type comprising an iron casing 11 with a lower internal ledge 12 and trunnions 13. The hot top may be supported temporarily in the position illustrated by means of blocks 14 which rest upon the mold and engage the trunnions 13 or other projecting parts of the casing. These blocks are intended to be knocked out as soon as the hot top is floated upon the metal poured into the mold.

Two courses of semipermanent lining blocks 15 and 16 are fitted to the tapered inner surface of the casing 11 and keyed in position by corner

blocks 17 and 18. Beneath the ledge 12 there is a refractory bottom ring 19 held in position temporarily by wire clips 20, the inner face of this ring being substantially flush with the inner faces 5 of lining blocks 16. Flow of hot metal upwardly between the hot top and the wall of the mold is delayed by sheet metal wiper strips 21 for a period long enough to insure the freezing of the metal there. The bottom ring 19 is used but once, and ordinarily adheres to the ingot when the hot top is stripped therefrom. The construction thus far described is a well known commercial construction.

In accordance with the present invention, certain 15 of the semipermanent lining blocks are modified to cause the sinkhead to be cast with projections on at least two opposed sides such that they may be engaged by the bits of an ingot crane to afford a better grip than can be obtained upon 20 the otherwise tapered surfaces of the sinkhead. To this end two oppositely positioned blocks, such as blocks 16 of the lower course, are formed with wedge-shaped recesses or cavities 22, the big end of the wedge being uppermost, as shown.

25 This cavity 22 may extend through the top surface 23 of the block, as herein illustrated, or it may begin below surface 23. The cavity may be molded in the block when the latter is manufactured or it may be formed in the block by grinding. The angle of the wedge is preferably 30 the same as the angle of slope or taper of the lining face. The wedge angle should not ordinarily be greater than the slope angle. If the said two angles are the same, the outer face 24 of the 35 cavity will lie in a vertical plane when the block is assembled in the hot top.

If the cavities 22 are left open, as in Fig. 4, the cast ingot will have a sinkhead with two opposed vertically walled projections which will offer 40 much better surfaces for engagement with crane bits than would be afforded by the tapered walls of the sinkhead. However, the invention may be carried a step further to produce beads or transversely extending projections 25 on opposite 45 walls of the sinkhead, one such bead appearing in Fig. 3. This result is effected by filling the cavities 22 of the lining with slurry flush with the adjoining faces of the lining block. The slurry used may vary considerably in composition. It should be a paste of such consistency as to retain its form after being put in place, and one which will not adhere strongly to the lining blocks after being subjected to the heat of the molten metal. After the cavities have been thus 50 filled with slurry, one or more transverse fur-

rows 26 may be formed in the slurry, as by wiping with a blunt instrument or the thumb or finger of the operator. These furrows may be straight, curved or angular. Now when the metal is cast, beads 25 will be formed on the sinkhead. When the hot top is stripped from the ingot, the baked slurry beneath the beads 25 will give way readily in front of the vertical faces 24, and no damage to the lining blocks will result. Hence in order to prepare the upper lining of the hot top for the next heat, it is necessary only to again apply the slurry and again wipe out the furrows 26.

The outer face of the cavity may be inclined somewhat upwardly and inwardly, especially if a long cavity is desired as in the case of the modification illustrated in Fig. 5, where a lower course block 30 has a cavity with a vertical rear wall 31 that registers with a cavity in an upper course block 32 the rear wall 33 of which may be inclined inwardly and upwardly away from the vertical. As illustrated, a series of furrows 34 are formed in the slurry with which the upper cavity is filled and a further furrow 35 is formed in the slurry filling the cavity of the lower block. Of course, one or more of these furrows may be omitted. In any event, the resulting bead or beads will clear the walls 33 and 31 when the hot top is stripped from the ingot.

Fig. 6 illustrates a somewhat extreme case in which a block is formed with a cavity having a rear face 36 inclined upwardly and outwardly away from the vertical and wherein a furrow 37 is formed in the slurry filling the cavity. Here the contraction of the sinkhead upon cooling is relied upon to move the bead 38 on the sinkhead 39 inwardly beyond the vertical plane 40 through the bottom edge of the wedge-shaped cavity. Such an arrangement is permissible where contraction is considerable, as in the case of large hot tops.

The cavities can be formed in either the top or the bottom course of a two-course lining or in any course of a more than two-course lining. The invention may also be employed in a composite hot top in which the lining is a one-piece refractory that is applied in the plastic state and dried, the baking being effected by the heat of the metal in the first use of the hot top thereafter. A lining of this sort may be termed a rammed lining and the cavities may be formed by projections on a core member employed to confine the plastic material while being rammed into place.

Now, when ingots with exposed sinkheads have to be loosened from their molds by a stripper crane or handled in the soaking pit building by soaking pit cranes, particularly if the exposed sinkheads grow cold, hard and smooth, the projecting vertical faces of the beads 25 afford excellent surfaces against which crane bits will lodge and the delays that would otherwise occur if the bits could not get a firm purchase on the sinkhead are eliminated. In addition to preventing delays, my invention also prevents damage to molds occurring when the molds have to be swung against rigid objects to dislodge the ingots. Ingots so dislodged generally have to be banked, to be rolled later, which interferes with orders and schedules.

Another difficulty overcome by the invention is that the dropping of ingots in and around the soaking pit building is eliminated, thereby reducing damage due to this cause which has been suffered heretofore by railroad tracks, rolling

stock, and soaking pit bottoms, particularly those of latest design with exposed buriers.

Having thus described my invention, I claim:

1. In a hot top shaped to provide an upwardly tapered sinkhead, a hardened refractory element the inner surface of which is formed with a cavity having an approximately vertical outer face which runs downwardly to the inner surface of the refractory element, whereby any projection formed upon the sinkhead within said cavity will not interfere with the stripping of the hot top from the ingot.

2. In a hot top shaped to provide an upwardly tapered sinkhead, a hardened refractory element extending throughout its perimeter to the bottom of the hot top the inner surface of the said element being formed with a horizontally extending furrow, said element having in the space vertically beneath said furrow plastic material adapted to give way readily when the hot top is stripped from the ingot.

3. In a hot top shaped to provide an upwardly tapered sinkhead, a hardened refractory element having in its inner surface a cavity of the shape of a wedge with its big end up, the angle of the wedge being approximately that of the taper angle of the hot top.

4. In a hot top shaped to provide an upwardly tapered sinkhead, a casing, two courses of semi-permanent lining blocks therein, each of two opposite blocks of the lower course having therein a cavity of the shape of a wedge with its big end up, said cavity extending from the upper end of the block downwardly, the angle of the wedge being approximately that of the angle of slope of the hot top lining, whereby opposed projections may be formed upon the lower portion of the sinkhead.

5. In a hot top shaped to provide an upwardly tapered sinkhead, a casing, two courses of semi-permanent lining blocks therein, each of two opposite blocks of the lower course having therein a cavity of the shape of a wedge with its big end up, said cavity extending from the upper end of the block downwardly, the angle of the wedge being approximately the same as the angle of slope of the hot top, the lower portion of said cavity being filled with slurry flush with the lining wall.

6. The method of providing ingot sinkheads with opposed outwardly extending beads or projections, which consists in the provision of hard refractory walls with cavities in exposed inner surfaces thereof, said cavities having approximately vertical outer faces, filling said cavities with slurry flush with the adjacent surfaces of the said walls, and forming transverse furrows in the slurry near the upper ends of the cavities in order to produce beads on the sinkhead when the metal is poured and solidifies in the hot top.

7. In a hot top shaped to provide an upwardly tapered sinkhead, a hardened refractory element exposed to the metal to be poured, said refractory element extending throughout its perimeter to the bottom of the hot top, said hot top having cavities in opposed inner surfaces of the shape of big end up wedges, said cavities being formed exclusively in said hardened refractory element, and being so dimensioned that when the sinkhead has cooled and the hot top is stripped from the ingot the projections formed in the cavities will clear the lining at the lower ends of the cavities.

BENJAMIN F. ANTHONY.
